DESIGN FOR A FINGER RING

John J. Gruen, South Orange, N. J., assignor to Moore & Son, Inc., Newark, N. J., a corporation of New Jersey

Application February 20, 1937, Serial No. 67,775

Term of patent 7 years

To all whom it may concern:

Be it known that I, John J. Gruen, a citizen of the United States, residing at South Orange, in the county of Essex and State of New Jersey,
have invented a new, original, and ornamental Design for a Finger Ring, of which the following is a specification, reference being had to the accompanying drawing, forming part thereof, in which Fig. 1 is a perspective view of one side and Fig. 2 a similar view of the opposite side of a finger ring showing my new design.

I claim:

The ornamental design for a finger ring, as shown.

JOHN J. GRUEN.
